ROBERT A. REYNOLDS, OF DETROIT, MICHIGAN

INTERNAL-COMBUSTION ENGINE

Application filed January 8, 1930. Serial No. 419,429.

This invention relates to an internal combustion engine, and has to do particularly with an engine designed in such manner that a power stroke of each piston is had in each 5 downward stroke of the piston. In other words, the invention aims to provide an internal combustion engine generally referred to as an engine of the two cycle type which differentiates from the conventional four 10 cycle type wherein a power stroke of a piston occurs only once every four strokes or in every other downward stroke.

An engine of this nature is shown in my Patent No. 1,695,823 granted December 18, 15 1928. In the engine of the patent, however, a sliding cross head was used in the cylinder construction which, together with the piston and sleeve, made the engine too great in over-all height for use in many places as, for example, automotive vehicles.

It is the object of the present invention to provide an engine which operates in the two cycle manner but wherein the over-all height is materially reduced over that required by 25 an engine shown in my patent and that the over-all height may be substantially the same as a similar four cycle engine. In carrying out this matter, the invention contemplates the provision of a construction for the purpose of forming a chamber immediately below the piston which chamber changes in size but which is provided with a novel construction closing the end of the sleeve in which the piston reciprocates. At the same 35 time the connecting rod extends through this closed end. The purpose of providing this chamber will be better understood as the description progresses in detail.

In the accompanying drawings:

40 Fig. 1 is a sectional view taken through an engine constructed in accordance with the invention illustrating the parts in the position assumed just prior to a power stroke.

Fig. 2 is a similar sectional view in illustration of the positioning of the parts after the power stroke has been substantially expended.

Fig. 3 is a similar sectional view in illustration of the position of the parts just prior 50 to the compression stroke.

Fig. 4 is a sectional view taken through the engine substantially at right angles to Fig. 1.

Fig. 5 is a sectional view taken on line 5-5 of Fig. 4 illustrating the eccentric for operating the sleeve.

55 Fig. 6 is a sectional view taken substantially on line 6-6 of Fig. 4 illustrating a squared formation in the cylinder for preventing of a twisting action.

Fig. 7 is a section taken through a bushing used for the sealing of the connecting rod.

In the drawings, a cylinder block is generally referenced 1, a crank case 2, and crankshaft 3. The cylinder block is provided with the usual cylindrical formation as at 4, within which there is reciprocably mounted a sleeve 5. Within this sleeve is a piston 6 having a connecting rod 7 which joins the piston to the crankshaft in the usual manner.

70 One end of the sleeve is closed as at 10 while the other end of the sleeve is equipped for the passage therethrough of the connecting rod 7, yet in such a manner as to form a sealed closure. For this purpose a closure member 11 is secured to the lower end of the sleeve as by means of screw threading the two together as at 12, and this member is connected as at 13 to a strap 14 mounted on an eccentric 15 on the crankshaft.

75 The member 11 is slotted as at 16 for the passage therethrough of the connecting rod, and inasmuch as there is a swinging movement of the connecting rod together with its relative longitudinal movement, the slot is made of sufficient length to take care of this swinging movement. Note Figs. 1 and 2. This slot is sealed for a purpose presently to be described. The connecting rod is preferably of uniform cross sectional dimension 80 for a considerable portion of its length so as to slidably fit what might be termed a bushing 20 fitted around the same. The bushing, as shown in Fig. 7, comprises two halves so that it can be placed around the 85 connecting rod, the halves being secured together by machine screws as shown.

Within the member 11 is a rocking sealing element 21 composed of two halves secured together by bolts 22 taken through aligned 90

ears in these halves. The sleeve or bushing 20 near its central portion, preferably has a bead or rounded formation 23 and the two halves of the rocker member 21 have each a rounded recess 24. When the two rocker members are placed together, the circumferential bead 23 fits in the groove so as to form a ball and socket type of connection permitting the bushing to rock in its mounting. Preferably, the bushing and rocker member are further secured together by means of pins 25 located on the axis of the ball and socket mounting and extending in the direction of extent of the crankshaft. Thus, while the bushing can rock in its mounting, such rocking movement takes place also on the fulcrum pins. As will be noted by reference to Fig. 4, at least one of the parts which forms the rocker member 21 has a leg 26 which extends downwardly through the opening in the closure member 11 and engages an underside thereof so as to tie the members together and prevent the rocker member from lifting from the curved seat formed by the member 11.

Accordingly, it will be noted that even though the connecting rod extends through the lower end of sleeve 5, the rocker member together with the bushing effectively closes and seals the slot 16 while the joint between the connecting rod and the bushing also provides for a seal. In this respect, it is to be pointed out that suitable packing material may be used wherever the same is found needful.

It is further to be pointed out that there is provided above the closed head of the sleeve 5 a compression chamber 30 while the combustion chamber lies between the head of the sleeve and the piston, as illustrated at 31. The usual spark plug is shown at 32 and the sleeve has an opening 33 which comes into alignment with the spark plug at the proper time, as illustrated in Fig. 4.

The operation of the engine will now be described and in giving this description reference will be made to the heretofore non-mentioned ports and passageways for raw fuel and exhaust gases and compressed air which is utilized for the purpose of blowing the exhaust gases out of the combustion chamber. Starting with the parts as shown in Fig. 1, wherein the parts are in the position assumed just prior to the power stroke, chamber 30 at this time is filled with a combustible mixture which has been drawn in through a port 40. The combustion chamber 31 is reduced in size and a combustible charge is therein compressed. When the charge is ignited by the spark plug the piston moves downwardly while the eccentric causes the sleeve to move upwardly, the parts in moved position being illustrated in Fig. 2. Here it will be appreciated that the charge in chamber 30 has been compressed.

Note also that chamber 41 positioned below the piston and defined at the lower end by the seal through which the connecting rod extends has been reduced in size and air which was in this chamber is compressed. At about the time the parts reach the position shown in Fig. 2, port 42 in the sleeve comes into alignment with the passageway 43 as does also the port 44. The compressed air in chamber 41 now flows into the combustion chamber 31 and at this time the exhaust port in the sleeve as illustrated at 45 comes into alignment with an exhaust port 46 leading to the atmosphere. The inflow of the compressed air discharges the spent exhaust gases.

As the parts continue to move, the passageway 43 is cut off, and port 47 moves into communication with passageway 48 which connects with the compression chamber 30. The compressed charge now flows into the combustion chamber. Some air is already in the combustion chamber and in this respect it might be pointed out that the compressed mixture of combustible fuel may be rather rich so that as it is rarefied by the air already in the combustion chamber a proper mixture will be had. The parts continue with the piston rising and the sleeve lowering until they again reach the position indicated in Fig. 1, thus compressing the combustible charge in chamber 31 with the sleeve sucking in a new charge of fuel through port 40. At this time the chamber 41 has enlarged thus creating a rarefied atmosphere therein and port 49 in the sleeve comes into registry with port 50 connecting to the atmosphere and due to the differential pressure, air enters the chamber 41 to be compressed in the next movement and passed through passageway 43 to blow out the exhaust gases.

As shown in the drawing, the various ports and passageways do not come into and out of registry at the precise mathematical moments; what is meant is there is an overlapping of the successive registering but this is common practice in internal combustion engines.

Accordingly, it will be noted that a two cycle engine construction is provided in which no use is made of the crank case for the passage of fuel therethrough and in which the over-all height of the engine is reduced so that such height is substantially the same as a similar four cycle engine.

An important feature to be noted is the off-center point of connection of the strap 14 with the sleeve at the point 13. This construction provides for a relatively idle period for the sleeve at its top and bottom positions with relatively fast reciprocable movement. For example, it will be noted by comparison of Figs. 2 and 3, that while the crank has moved a considerable distance the sleeve has not moved far but will descend rapidly soon

after the position shown in Fig. 3. This off-center connection tends to set up a twisting action. This may be overcome in a number of ways and in the present instance is overcome by providing a flat in the member 11 as illustrated at 11^a, and a corresponding flat on the cylinder wall. By referring to Fig. 4, it will be noted that one eccentric is used to a cylinder; two may be used, one on each side 10 of the crank and this would stop the twisting action.

Claims:

1. In an internal combustion engine the combination with a cylinder, a sleeve therein having a closed end, a piston in the sleeve, a crankshaft, a connecting rod connecting the piston and crankshaft and extending through one end of the sleeve, means for reciprocating the sleeve, and means for sealing the end of the sleeve through which the connecting rod extends, said sealing means comprising an element movable with respect to the sleeve.

2. In an internal combustion engine, the combination with a cylinder, a sleeve therein having a closed end, a piston in the sleeve, a crankshaft, a connecting rod connecting the piston and crankshaft and extending through one end of the sleeve, means for reciprocating the sleeve, means for sealing the end of the sleeve through which the connecting rod extends, said sealing means comprising an element movable with respect to the sleeve, and another element sealing against the connecting rod and movable with respect thereto.

3. In an internal combustion engine, the combination with a cylinder, a sleeve therein having a closed end, a piston in the sleeve, a crankshaft, a connecting rod connecting the piston and crankshaft and extending through one end of the sleeve, means for reciprocating the sleeve, means for sealing the end of the sleeve through which the connecting rod extends, said sealing means comprising an element movable with respect to the sleeve, and another element sealing against the connecting rod and movable with respect thereto, said two elements of the sealing means being movably mounted with relation to each other.

4. In an internal combustion engine, the combination with a cylinder, a sleeve therein having a closed end, a piston in the sleeve, a crankshaft, a connecting rod connecting the piston and crankshaft and extending through one end of the sleeve, means for reciprocating the sleeve, means for sealing the end of the sleeve through which the connecting rod extends, said sealing means comprising an element movable with respect to the sleeve, and another element sealing against the connecting rod and movable with respect thereto, said two elements of the sealing means being movably mounted with relation to each other, and said mounting comprising a ball and socket type joint.

5. In an internal combustion engine sub-

stantially of the type described a piston, a crankshaft, a connecting rod joining the two, a sleeve in which the piston moves, means for reciprocating the sleeve in timed relation to piston movements, a substantially half-spherical member closing the end of the sleeve through which the connecting rod projects, said member being slotted for the reception of the connecting rod, and means sealing against the connecting rod and allowing the same to reciprocate therethrough, and sealing against the said member to close the slot.

6. In an internal combustion engine substantially of the type described a piston, a crankshaft, a connecting rod joining the two, a sleeve in which the piston moves, means for reciprocating the sleeve in time relation to piston movements, a substantially half-spherical member closing the end of the sleeve through which the connecting rod projects, said member being slotted for the reception of the connecting rod, and means sealing against the connecting rod and allowing the same to reciprocate therethrough and sealing against the said member to close the slot, said means being rockable in the half-spherical member to accommodate for angular positions of the connecting rod.

7. In an internal combustion engine substantially of the type described, a piston, a crankshaft, a connecting rod joining the two, a sleeve in which the piston moves, means for reciprocating the sleeve in timed relation to piston movements, a substantially half-spherical member closing the end of the sleeve through which the connecting rod projects, said member being slotted for the reception of the connecting rod, means sealing against the connecting rod and allowing the same to reciprocate therethrough and sealing against the said member to close the slot, said means being rockable in the half-spherical member to accommodate for angular positions at the connecting rod, and means on the sealing member projecting through the slot and overlying an outside surface of the half-spherical member.

8. In an internal combustion engine substantially of the type described, a piston, a crankshaft, a connecting rod joining the two, a reciprocable sleeve in which the piston moves, a half-spherical shaped member associated with the end of the sleeve and having a slot through which the connecting rod extends, sealing means fitting into the half-spherical member for closing the slot, a bushing connected to the sealing means for sealing against the connecting rod and through which the same reciprocates, said sealing means having a curved face so that the same is rockable in the half-spherical member.

9. In an internal combustion engine substantially of the type described, a piston, a crankshaft, a connecting rod joining the two,

a reciprocable sleeve in which the piston moves, a half-spherical shaped member associated with the end of the sleeve and having a slot through which the connecting rod extends, sealing means fitting into the half-spherical member for closing the slot, a bushing connected to the sealing means for sealing against the connecting rod and through which the same reciprocates, said sealing means having a curved face so that the same is rockable in the half-spherical member, and a ball and socket type connection between the bushing and said sealing means.

10. In an internal combustion engine substantially of the type described, a piston, a crankshaft, a connecting rod joining the two, a reciprocable sleeve in which the piston moves, a half-spherical shaped member associated with the end of the sleeve and having a slot through which the connecting rod extends, sealing means fitting into the half-spherical member for closing the slot, a bushing connected to the sealing means for sealing against the connecting rod and through which the same reciprocates, said sealing means having a curved face so that the same is rockable in the half-spherical member, a ball and socket type connection between the bushing and said sealing means, and fulcrum pins joining the bushing and sealing means which are located on the line of fulcruming of the bushing in the sealing means.

11. In an internal combustion engine substantially of the type described, a piston, a crankshaft, a connecting rod joining the two, a reciprocable sleeve in which the piston moves, a half-spherical shaped member associated with the end of the sleeve and having a slot through which the connecting rod extends, sealing means fitting into the half-spherical member for closing the slot, a bushing connected to the sealing means for sealing against the connecting rod and through which the same reciprocates, said sealing means having a curved face so that the same is rockable in the half-spherical member, a ball and socket type connection between the bushing and said sealing means, said sealing means having a part which projects through the slot in the half-spherical member and engages over its outer surface to hold the sealing means assembled with the half-spherical member.

In testimony whereof I have affixed my signature.

ROBERT A. REYNOLDS.
